CLAIM

(51) **LOC (10) Cl.** **14-04**

The ornamental design for a tab area search tool for a display screen, as shown and described.

(52) **U.S. Cl.**

DESCRIPTION

USPC **D14/485**
CPC **G06F 3/04817** (2013.01)

A portion of the disclosure of this patent document contains material which is subject to copyright protection. The copyright owner has no objection to facsimile reproduction by anyone of the patent document or the patent disclosure, as it appears in the Patent and Trademark Office patent file or records, but otherwise reserves all other copyright rights whatsoever.

(58) **Field of Classification Search**

USPC D14/485–495; 715/700–867
CPC G06F 3/0481–3/0486

See application file for complete search history.
